Patented Oct. 19, 1920.

UNITED STATES PATENT OFFICE.

HAROLD W. HARRIS, JR., OF ROANOKE, VIRGINIA.

BAG-HOLDER.

1,356,142.

Specification of Letters Patent.

Patented Oct. 19, 1920.

Application filed June 10, 1920. Serial No. 387,904.

To all whom it may concern:

Be it known that I, HAROLD W. HARRIS, Jr., a citizen of the United States, residing at Roanoke, in the county of Roanoke and State of Virginia, have invented certain new and useful Improvements in Bag-Holders, of which the following is a specification.

This invention relates to bag holders and has special reference to devices for supporting coal bags in position to be filled, the object being to provide a device of simple and inexpensive construction which will relieve the bag of all strain while it is being filled and thereby prolong the life of the bag.

The invention is illustrated in the accompanying drawings and will be herein-after fully described and claimed.

20 In the drawings—

Figure 1 is a perspective view of my improved bag holder showing the same in its operative position;

Fig. 2 is an enlarged detail section on the line 2—2 of Fig. 1;

Fig. 3 is an enlarged detail section on the line 3—3 of Fig. 1.

In carrying out the invention, I employ a supporting frame consisting of an annulus 1 of metal and legs 2 secured rigidly to the said annulus and of such a height that they will support the annulus above the ground or the floor at a height corresponding to the usual height of coal bags. The annulus 35 may conveniently be formed from a flat bar or strip of metal having its ends welded or otherwise permanently united and the supporting legs 2 may be of similar material and riveted or otherwise rigidly secured at 40 their upper ends to the said annulus. The lower ends of the supporting legs will preferably be slightly flared outwardly, as shown at 3, as greatest stability is thereby imparted to the device. At diametrically 45 opposite points of the annulus or band 1, I provide the upstanding lugs or hooks 4 which as illustrated may conveniently be short plates of bar metal riveted or otherwise rigidly secured to the band and projecting above the same, the upper portions of these lugs being deflected slightly outwardly, as shown most clearly in Fig. 3, so that the handles of the bag when engaged over these retainers will be effectually held.

At intervals upon the band or annulus 1, I 55 secure the keepers 5 which may also conveniently be short lengths of bar metal rigidly secured at their upper ends to the band. Intermediate their ends these members 5 are bent sharply inwardly, as shown 60 at 6, and then carried downwardly and slightly outwardly, as shown at 7, the portions 6 and 7 being adapted to engage over the edge of the bag and hold the mouth thereof distended as will be readily understood. The bag 8 is the usual canvas bag now generally employed in the retail delivery of coal and is of such a height that when in position within the bag holder its bottom will rest upon the ground or the 70 floor. The handles 9 are engaged over the retainers 4 and the beaded hem 10 of the bag is engaged under and against the outer sides of the retainers 5, as clearly shown. The bag will thus be held open and will be 75 supported so that it may be easily filled, and the strain upon the handles 9 is minimized inasmuch as the weight of the coal is not thrown thereon but will be carried by the ground or the floor upon which the 80 bottom of the bag rests.

My device is exceedingly simple in its construction and may, therefore, be manufactured at an extremely low cost while it will be found highly efficient in use for the 85 purposes for which it is designed. The mouth of the bag will be held fully distended so that the coal may be easily placed in the bag and when it is filled the handles 9 may be easily lifted off the retainers 4 so 90 that the filled bag may be carried to its destination. The holder is light and may be easily shifted from point to point as the occasion for its use arises.

Having thus described the invention, what 95 is claimed as new is:

1. A bag holder comprising a supporting frame, upstanding rigid retainers fixed on said frame and projecting above the same, and rigid keepers fixed on the frame between the retainers and depending below the plane of the retainers whereby a bag provided with handles may be engaged around the keepers and have its handles engaged over said retainers and the bag 105 thereby supported and held distended.

2. The improved bag holder herein described and shown comprising an annular

band, supporting legs secured rigidly to and depending from said band, upstanding retainers rigidly secured to said band and projecting above the same, the upper portions of said retainers being deflected outwardly, and keepers secured to the band and depending therefrom, said keepers hav-

ing their intermediate portions extended sharply inwardly and their lower portions deflected outwardly and downwardly from 10 said inwardly extended intermediate portions.

In testimony whereof I affix my signature.
HAROLD W. HARRIS, Jr. [L. S.]
